UNITED STATES PATENT OFFICE.

FREDERICK THOMAS BUCKTHORPE AND ANDREW BARTER, OF LONDON, ENGLAND.

BOX, CIGARETTE, AND LIKE CASE.

Application filed April 11, 1925, Serial No. 22,472, and in Great Britain September 18, 1924.

This invention relates to boxes, such as cigarette cases of the type in which the lid is hinged to a strip slidably connected to the box and in which the lid has sliding movement relative to the box to free or engage the catch or fastening means between the box and the lid.

In boxes of the character just referred to an open gap or space is usually left in the sliding means into which dust or dirt can enter and prevent the full sliding movement and proper action of the box. In addition, in boxes of this character sliding means usually employed takes up some amount of room and consequently reduces the capacity of the box.

The principal object of this invention is to construct such a box that the sliding means are entirely covered or closed, thus preventing dust or dirt from accumulating in the sliding joint. A further object is to locate the sliding means in the ordinary thickness of the wall of the box instead of within the box so that the capacity of the box is not reduced.

According to this invention we hinge the lid in the usual manner to the box, a strip of which the outer face is provided with projections through which a pin or wire extends and with longitudinal grooves or recesses between said projections. On the upper edge of one wall of the box we form similar pin or wire receiving projections and longitudinal grooves or recesses between said projections.

The projections of the strip and box are spaced equidistantly apart and the space between adjacent projections is longer than the length of the projections and the projections are so arranged on the strip and box that when the lid and box are assembled the projections of the strip and box will be positioned between one another in the grooves or recesses with the holes of the projections in longitudinal alignment to receive a pin or wire which secures said parts together.

Our invention will be clearly understood from the following description in connection with the annexed drawings, in which—

Figure 1 is a plan view of an open cigarette case embodying this invention.

Figure 2 a section on the lines aa of Figure 1 showing the position of the parts when the lid is in the normal closed position.

Figure 3 a view similar to Figure 2 showing the lid as moved relatively to the box

to disengage the catch which normally holds the lid closed.

Figure 4 a section on the line bb , Figure 1, and Figure 5 a section on the line cc 60 of Figure 1.

As shown in the drawings we employ a strip 1 which is hinged at 2 to the lid 3 in a known manner and on the outer side of the strip 1 we form or attach a series of tubular projections 4 and between each adjacent pair of projections 4 we form a longitudinal half circular groove or recess 5, the centre line of the holes in the projections being approximately level with the outer face of the 70 strip. On the wall 6 of the box 7 we form or attach a similar series of tubular projections 8 as well as a groove or recess between each adjacent pair of projections.

The projections 4 and 8 are arranged preferably equidistantly apart with a longer space between each adjacent pair than the length of the projections and so positioned in relation to each other that the strip 1 can be placed on the wall 6 of the box 7 with 80 the tubular projections 4 of the former arranged between the projections 8 of the latter, the projections 4 of the strip being seated in the grooves of the box, and the projections 8 of the box extending into the 85 grooves of the strip as shown in Figures 2, 4 and 5. In this position the holes in the projections 4 and 8 will be in longitudinal alignment and a pin or wire 9 is passed through same to hold the strip 1 securely 90 against the wall 6 of the box 7. The holes in the tubular projections 4 of the strip 1 are formed to have a sliding fit on the pin or wire 9 so that the strip 1 and lid 3 can be slid backwards and forwards longitudinally on the pin or wire 9, the extent of movement being limited by the amount of space 10 between the two sets of projections 4 and 8, that is to say, by the difference between the lengths of the spaces and of the 100 projections.

The strip 1 is made the same width as the wall 6 of the box 7.

11 is the usual hook catch on the lid adapted to engage in a slot or keeper 12 on 105 the box when closed.

When the lid is in its normal closed position the box 7 and strip 1 with lid 3 are in the position shown in Figure 2 with the hook 11 engaged under one end of the slot 110 or keeper 12. To open the box the lid 3 and with it the strip 1 are slid longitudinally

of the pin or wire 9 to the position shown in Figure 3 when the hook 11 will be free of the end of the slot or keeper 12 and the lid can be opened on its ordinary hinge 2. Preferably the hinge 2 is provided with the usual spring arrangement so that the lid will open through the action of the spring when the hook 11 is disengaged from the end of the slot or keeper 12.

- 10 In a box constructed according to this invention the sliding means are totally enclosed between the strip and wall 6 of the box and thus is practically dust proof, and the wall of the box may be of the same thickness as the ordinary wall so that the capacity of the box is not decreased.

It will be understood that the projections and grooves or recesses may be formed in any suitable manner.

- 20 What we do claim as our invention and desire to secure by Letters Patent is:—

1. A box or the like comprising a pair of members constituting, respectively, a receptacle and a lid for said receptacle, a strip 25 hingedly connected to an edge of one of said members, one of the faces of said strip being provided with a plurality of depressions and projections alternately arranged in longitudinal alinement, the other of said members 30 having adjacent one of its edges a plurality of depressions of greater length than the projections of said strip into which said projections extend, said latter member also having a plurality of projections longitudinally alined with said last-named depressions and 35 of less length than the depressions of said strip and projecting into the latter, and a

pin extending longitudinally through the projections of said strip and of said last-named member, one of said members having a keeper and the other member having a catch adapted to engage with and disengage from said keeper when said members are moved relatively to one another in opposite directions lengthwise of said strip.

2. A box of the character described, comprising a box body and a lid therefor, a strip hingedly connected to a longitudinal edge of said lid, the outer face of said strip having a plurality of depressions and projections alternately arranged in longitudinal alignment, one of the longitudinal walls of said box body having on its edge a plurality of depressions and projections alternately arranged in longitudinal alignment 55 to respectively receive and project into the projections and depressions of said strip, the depressions of said strip and box body being respectively of greater length than the projections thereof, said projections having longitudinally aligned bores of which the axes are substantially in the plane of the outer face of said strip, a pin extending longitudinally through the bores of said projections, and complemental catch members 60 carried by said box and said lid and adapted to engage with and disengage from one another during relative movement of said lid and box body in the direction of the length of said strip.

In testimony whereof we have hereunto set our hands.

FREDERICK THOMAS BUCKTHORPE.
ANDREW BARTER.
